UNITED STATES PATENT OFFICE.

THOMAS H. WALKER, OF MULLAN, IDAHO.

CURRENT-MOTOR.

1,034,940.

Specification of Letters Patent. Patented Aug. 6, 1912.

Application filed December 28, 1911. Serial No. 668,259.

To all whom it may concern.

Be it known that I, THOMAS H. WALKER, a citizen of the United States, residing at Mullan, in the county of Shoshone and State of Idaho, have invented certain new and useful Improvements in Current-Motors; and I do declare the following to be a full, clear, and exact description of the invention, such as will enable others skilled in the art to 10 which it appertains to make and use the same.

This invention relates to improvements in current motors.

The object of the invention is to provide 15 a current motor which will be simple, strong, durable and inexpensive in construction, efficient and reliable in operation and which is particularly adapted for elevating water for irrigating purposes.

With this and other objects in view the invention consists of certain novel features of construction, and the combination and arrangement of parts as will be more fully 20 described and claimed.

In the accompanying drawings:—Figure 1 is a side view of my improved current motor; Fig. 2 is a top plan view; Fig. 3 is an end view thereof; Fig. 4 is a vertical cross section on the line 4—4 of Fig. 1; 25 Fig. 5 is a detail perspective view of the brake mechanism of the motor; Fig. 6 is an enlarged detail view of one of the hubs for the spokes forming the ends of the cable supporting drums.

My improved current motor comprises a suitable frame 1 provided with standards 2 which are set into the bed of the stream in which the motor is to be arranged. In the frame 1 at suitable distances apart are arranged bearings 3 and 4. In the bearings 3 and 4 are revolvably mounted cable supporting drums 5 and 6 each of which comprises a shaft 7 having fixedly mounted thereon at suitable distances apart, hubs 8. The hubs 8 have formed thereon a series of radially projecting spoke attaching arms 9 to which are bolted the inner ends of a series of radially projecting spokes 10 the outer ends of which are secured to annular rims 11. The spokes 10 and rims 11 form the ends or heads of the cable supporting drums 5 and 6 and said ends or heads are connected together by annular plates of suitable width having therein a plurality 50 of water discharging passages or as shown

in the drawings, said heads may be connected together by a series of segmental plates 12 spaced apart to form a plurality of water discharging passages through which the water may freely flow as the 60 drums are rotated in the stream.

Arranged around and secured to the segmental plates forming the annular surface of the drums are two or more annular cable receiving channel shaped rings or bands 13 65 which provide grooves or channels to receive the blade supporting and drum operating cables 14 which are engaged therewith and have secured thereto at suitable intervals a series of drum operating blades 70 or paddles 15. The paddles 15 are in the form of plates or boards of suitable width and having a length corresponding approximately with the length of the drums, said plates or boards being secured to the bars 75 or cleats 16 the inner ends of which are connected by eyes or loops 17 with the cables 14. The outer ends of the cleats are connected by short chains or cables 18 to the outer operating cables 14 whereby the blades 80 or paddles are held in an operative position against the pressure of the current, said pressure of the current thus being applied to the cables 14 to turn the drums.

On the supporting frame 1 at suitable 85 positions are arranged platforms 19 upon which an operator may stand when adjusting or repairing any of the parts of the motor and for regulating the braking mechanism by which the speed of the motor 90 is controlled. The braking mechanism is arranged to be engaged with the drum 6 and comprises a brake bar or beam 20 which is supported by posts or standards 21 the lower ends of which are loosely engaged 95 with one of the platforms 19. Secured to the brake bar or beam 20 are brake shoes 22 having segmental outer surfaces adapted to be brought into engagement with the annular surface or side of the drum 6 with 100 greater or less pressure thereby retarding the movement of said drum and through the same the movement of the cables 14 and the drum 5 to a greater or less extent as may be desired. The brake bar or beam 20 is 105 adjusted to bring the brake shoes into greater or less forcible engagement with the outer surface of the drum by means of brake adjusting rods 23, the inner ends of which are loosely connected with the shaft 110

7 of the drum 6 adjacent to the ends of the latter as shown. The outer ends of the rods 23 are engaged with apertures in the bar or beam 20 and said ends are threaded and 5 provided with adjusting nuts 24 having operating handles 25 whereby they are readily turned on the rods to adjust the brake bar and thus draw the brake shoes into operative engagement with the angular side of 10 the drum 6, thus retarding the movement of the motor.

Bolted or otherwise firmly secured to the spokes forming one of the heads of the drum 5 is a sprocket gear 26 which, if desired may 15 be formed by a plurality of segmental sections and with which is engaged a drive chain 27 whereby the movement or power of the motor is transmitted and applied to the mechanism or apparatus to be driven by 20 the motor. In the present instance the motor is shown as being employed for operating a water elevating apparatus comprising a tower or elevator frame 28 in which are arranged water conducting pipes 29 connected 25 at their lower ends to a conducting pipe 30 and having their upper ends projecting a considerable distance above the tower and forming the upper portion thereof. On the upper ends of the pipes 29 is arranged a 30 tank supporting frame 31 on which is arranged a water tank 32 to the bottom of which the upper ends of the pipes 29 are connected. To the upper portion of the pipes 29 and to the frame 31 are secured inclined brace bars 33 on the upper ends of 35 which are arranged bearings in which is revolvably mounted the upper shaft 35 of an endless water elevator. On the shaft 35 are fixedly mounted sprocket gears 36 with 40 which are engaged the upper portions of endless water elevator chain 37 to which is attached at suitable intervals water elevating buckets 38 and which has its lower portion engaged with and driven by sprocket 45 gears 39 fixed on a conveyer operating shaft 40 journaled in suitable bearings in the lower portion of the tower and on which is also fixed a sprocket gear 41 with which the drive chain 27 from the sprocket gear 21 is 50 connected. By thus connecting the motor with the water elevating mechanism herein shown and described it will be seen that the water of the stream will be elevated by the buckets 38 of the conveyer and discharged 55 into the tank 32 from which the water will

be conducted by the pipes 29 and 30 to the place where the same is to be used.

It will thus be seen that my improved motor is particularly adapted for operating a water elevating apparatus for producing a supply of water for irrigating purposes.

My improved motor requires little or no attention, is economical in use as there is practically no expense in connection with the operation after the same has been installed, and the motor is composed of comparatively few parts which are not liable to get out of order or to require adjustment.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described my invention, what I claim is;

A current motor comprising a supporting frame, cable supporting drums revolvably mounted in said frame, said drums comprising heads each of which consists of a hub having radially extending arms, a series of spokes secured at their inner ends to said arms, annular bands connecting the outer ends of the spokes and segmental plates secured to said bands to form the outer annular surface of the drums, annular channel shaped cable receiving rings secured to said annular surface of the drums, operating cables engaged with said channel shaped rings whereby the drums are operatively connected together and driven, a series of blades having a loose connection with said cables, a braking mechanism adapted to be engaged with one of said drums whereby the speed of the motor is retarded, and a power transmitting gear fixed to the co-acting drum whereby the power of the motor, may be transferred.

In testimony whereof I have hereunto set my hand in presence of two subscribing witnesses.

THOMAS H. WALKER.
